UNITED STATES PATENT OFFICE.

THOMAS C. BUDDINGTON, OF PASADENA, CALIFORNIA, ASSIGNOR OF ONE-HALF TO
SAMUEL G. ELAM, OF PASADENA, CALIFORNIA.

DRILLING-BIT.

1,347,774.

Specification of Letters Patent.

Patented July 27, 1920.

Application filed May 22, 1919. Serial No. 298,978.

To all whom it may concern:

Be it known that I, THOMAS C. BUDDINGTON, a citizen of the United States, residing at Pasadena, in the county of Los Angeles 5 and State of California, have invented new and useful Improvements in Drilling-Bits, of which the following is a specification.

This invention relates to drilling bits for oil and other wells, and it has for its object 10 to provide an improved bit, particularly adapted for the drilling of deep wells in which casing is sunk or lowered in the hole as the drilling proceeds, the invention having for a particular object the provision of a 15 drilling bit which will enable the drilling operation to be carried on, and the casing to be lowered, without the use of devices known as "underreamers," for cutting away or drilling away or boring away the earth 20 formation beneath the casing. Ordinarily this "shoulder" or annular formation has to be removed, intermittently, by the substitution of an underreamer for the drilling bit, inasmuch as the ordinary drilling bit, in 25 the "standard" or reciprocating type of drilling apparatus, only cuts a hole with a diameter approximately as large as the inner diameter of the casing. In other words, with the present invention, I provide a 30 drilling bit which is expandable in nature, and the cutters of which, while contracted when lowering the bit through the casing, automatically expand after escaping at the 35 lower end of the casing, and occupy a spread-out position causing them to drill or bore out the earth formation to a diameter of hole sufficiently great to permit the casing to be lowered or to "follow" the bit without any underreaming operation.

40 All the loss of time incident to substituting underreamer for bit, and bit for underreamer, in ordinary "standard" drilling practice, which involves the intermittent withdrawal of the whole string of drilling 45 tools from the well, is thus obviated in the use of the present invention, and also the expense incident to purchase or rental, and to maintenance and repair, of underreamers is avoided.

50 The invention has for further objects the provision of an improved drilling bit which will be superior in point of relative simplicity and inexpensiveness of construction, taken in conjunction with convenience in 55 use, durability, positiveness in action, and

reliability, and which will be generally superior in efficiency and serviceability.

With the above and other objects in view, the invention consists in the novel and useful provision, formation, construction, combination, association and inter-relation of parts, members and features, all as herein-after described, shown in the drawing, and finally pointed out in claims.

65

In the drawing:

Figure 1 is a fragmentary side elevation, partly in section, of a drilling bit and part of the drilling string or drilling apparatus for producing wells, a part of the well casing being illustrated likewise, and the whole 70 being constructed and inter-related in accordance with the invention;

Fig. 2 is a view similar to Fig. 1 showing the cutters of the bit in expanded position, or positions of expansion, which positions 75 are assumed after the cutters have passed beneath the bottom of the well casing, such cutters being shown in contracted position or condition of contraction, in Fig. 1; and

Fig. 3 is a detail transverse sectional view, 80 taken upon the line a^3-a^3 , Fig. 1, and looking in the direction of the appended arrows.

Corresponding parts in all the figures are designated by the same reference characters.

Referring with particularity to the drawing, A designates the stem of the improved bit, provided at its upper end with a shackle 85 a pivoted to the stem as at 4, and by which shackle the bit is connected with the drilling rope or cable or other drilling tools, if required or desired, such as jars. At the lower end of the stem A is provided the bit stock b, which is preferably rectangular in cross-section, and provided at each of its four faces with a separate cutter B, such cutters

90 being mounted in connection with the stock b of the bit, so that the cutters have a tendency to swing outwardly at their lower ends, from the positions indicated in Fig. 1, to the positions in Fig. 2, when such cutters 95 are freed from confinement, as for instance, when they have passed the lower end of the casing, C, which is lowered in the well hole in the earth formation D, as the drilling or boring of the well advances. 5 designates a 100 shoe at the lower end of the casing, in accordance with customary practice. Preferably the cutters B consist of elongated flat metallic bodies 6, which are pivotally connected each in flat slidable contact with a 105

110

separate flat face 7 of the bit stock *b*, being so pivotally connected through the agency of two bolts 8, which are passed transversely through the bit stock *b*, at right angles to each other, and one above the other, projecting sufficiently beyond opposed faces 7 of the bit stock to receive and accommodate the upper ends of the cutters *B*, which have suitable openings to receive such bolt ends. 5 Nuts 9 are applied to the bolt ends exteriorly of the bit bodies 6, retaining the same in place in pivotal mounting upon such bolt ends. The holes which accommodate such bolt ends are formed at one side of the longitudinal center or median zones of the cutters, so that the cutters have an inherent 10 tendency to swing out at their lower sharpened cutting edges 10, in a series extending around the stock *b* uniformly, so that in proceeding around the stock in one direction a corresponding direction of projection of the expanded cutters exists. Thus, when the cutters are in expanded positions as shown in Fig. 2, they comprise a working group of 15 uniformly expanded cutters, their expansion being limited by stop means *E* which preferably consist of stop pins 11 disposed adjacent to the top portion of the stock *b*, one for each face 7 of such bit stock, and slightly 20 disposed at one side of a vertical plane passing through the pivotal center of the corresponding cutter body, being so disposed at that side of such plane as corresponds with the location of the narrower side of the pivotally suspended cutter body. In other 25 words, each stop pin is disposed slightly more eccentrically with respect to the corresponding cutter, that is, to its point of pivotal support. As clearly shown in Fig. 2, each cutter swings up against its stop pin 11, at the upper edge of the cutter, when such 30 cutter is in expanded or projected position at its lower edge, and the up-thrust of the cutter, resulting from its engagement with the earth formation, in reciprocation of the 35 cutter in drilling, is imparted to the bit stock through the respective bolt 8 and stop pin 11. The cutters automatically expand when liberated from the confining or restraining casing, and assume positions 40 shown in Fig. 2, in which positions they act to chip or cut away the formation and develop well hole, upon their reciprocation which is produced by the walking beam at 45 the surface of the well, in the ordinary manner.

I have shown a circulation system for the bit, the softening action of the liquid supplied by which assists the bit in the cutting 50 operation, and produces a mud or detritus in suspension which is bailed out of the hole or otherwise withdrawn. This circulation system includes a casing *F* applied to the bit stem *A*, so as to provide a chamber *f* surrounding the bit stem, the casing to that end

having a central tubular portion 12 which receives and accommodates the bit stem *A*, such casing *F* being held in position of adjustment in connection with the stem by one or more set screws 13 applied to the bit stem 70 through an upward projection 13^a upon the top of the tubular portion 12. A circular pipe 14 enters the upper portion of the closed casing *F*, and supplies the casing with liquid, whereas discharge pipes 15 range 75 downwardly from the lower portion of the casing, in a series of four, one for each cutter *B*, and each such discharge pipe being disposed slightly outwardly of the corresponding cutter and so as to discharge its 80 fluid downwardly into the zone of the cutting operation of the cutter.

It is believed that no further statement of the operation of the invention, or of its advantages, will be required, in addition to 85 that above given, inasmuch as it will be obvious that the expanded cutters will chip and cut and break away the formation, upon reciprocation of the bit in the drilling operation, the cutters automatically expanding to 90 their working positions after they have passed beneath the lower end of the casing, and automatically enter the casing, or collapse, upon the elevation of the drilling string. The cutters will effectively reduce 95 the earth formation to produce a hole having a diameter slightly greater than the outer diameter of the casing and its shoe, or sufficiently large to permit the casing to be lowered or driven down without the use 100 of any underreamer or underreaming operation, thus saving a large amount of time and expense, in interchange of bit for underreamer and underreamer for bit, and in cost of underreaming tools and the expense of 105 maintenance thereof. All of this makes for speedy and effective drilling action, and the cutter and bit in actual practice is found to "make hole" rapidly and effectively, particularly in shale and other softer formations. It is to be further noted that the casing *F* is adjustably connected with the bit stem *A*, so that its position may be shifted to vary the height above the lower ends 110 of the cutters *B*, at which height the liquid is to be discharged or released from the discharge pipe 15, all in accordance with preference or requirements of service.

It is obvious that many changes and variations may be made, with respect to the foregoing description and the showing of the drawing, in practising the invention, and in adapting the invention to varying conditions of use and service, without departing from the true spirit of the invention.

Having thus disclosed my invention, I claim and desire to secure by Letters Patent:

1. A bit, comprising a bit stock provided with a cutter eccentrically suspended from the bit stock and thus having an inherent 130

tendency to project laterally into drilling position; in combination with liquid circulation means comprising a casing, means for connecting the casing with the bit stock, 5 and a liquid supply pipe extending to the casing; said casing being adjustably mounted.

2. A bit, comprising a bit stock provided with a cutter eccentrically suspended from the bit stock and thus having an inherent 10 tendency to project laterally into drilling position; in combination with liquid circulation means comprising a casing, means for connecting the casing with the bit stock, 15 and a liquid supply pipe extending to the casing; said bit stock being provided with a stem upon which said casing is mounted above the bit stock.

3. A drilling bit, comprising a bit stock, and a plurality of eccentrically pivoted cutters mounted in connection with said bit stock and having an inherent tendency toward lateral projection at their cutting portions; bolts being provided through said bit stock and projecting beyond opposite faces 20 thereof, said cutters being mounted upon said projecting bolt ends, means being provided exteriorly of the cutters to prevent displacement thereof from the bolt ends. 25

In testimony whereof, I have signed my 30 name to this specification in the presence of two subscribing witnesses.

THOMAS C. BUDDINGTON.
